FOOTBALL SIDE LINE MARKER

Charles F. Volz, Baltimore, Md.

Application November 10, 1947, Serial No. 784,945

1 Claim. (Cl. 273—55)

1

This invention relates to games of the football class and more particularly to means employed for retaining the position of the "down" and "ten yard" markers when it becomes necessary to move them when the players approach the side lines or when the sticks are moved inadvertently.

In the playing of the conventional American football game, a rectangular field is employed. It is 300 feet long between the goal lines and 160 feet wide between the side lines or borders. Cross lines are visibly marked 5 yards apart on the ground transversely across the field between the side lines. The two goals are designated by posts erected perpendicularly on the end line as noted in the drawings. The game is played with an egg-shaped ball called a football as is well known. In playing the game, the football is generally carried, thrown or passed, and sometimes kicked with the feet. The game is played with two teams comprising eleven men on each side or team. Each team is the holder of the ball officially in turn, according to the event occurring during the playing of the game. When the team officially holding the football plays, it is encumbent on it to make at least ten yards longitudinal advance towards its opponent's goal in the next four consecutive plays, if it can hold the ball that long.

To keep track of this advanced yardage, certain officials or umpires assigned to the game, mark the point of beginning at the first "down." This is where the ball starts from in the first play. A long stick having a flag on its upper end and called a "down" flag is inserted into the ground at this point and is connected to a second similar stick and a flag by a marking chain which separates the flags by ten yards. This second flag stick called the "ten yard" marker is moved so the chain will become taut when pulled on and the stick is then pressed into the ground at that point and remains there for a predetermined period. Both of these flags are vertically set up in the ground in the space outside of the playing field, but adjacent to its border line and held in these positions by certain of the game officials. If the team holding the ball is able to carry the ball any distance towards its opponent's goal line and is stopped, then one of the officials locates the "down" indicator at this point, to show the advance made on this the second down. If the next play increases the distance gained or advanced, the "down" indicator is then moved to this point to show the gain on the third down. If the next play also increases the distance gained, then the "down" indicator is moved to that point and the "down" flag inserted in the ground at that point. If the sum total of the four downs shows a gain of ten yards or over, measured from the

2

point where the first down was marked off, then the same side retains the ball, the "down" flag is moved to that point and the ten yard chain is again stretched and the ten yard marker flag is inserted in the ground, and the game is continued. In the event any of the plays results in a loss of distance or ground, such loss is subtracted from the point of the last previous down.

In placing the sticks vertically at these locations, they are empressed in the ground deep enough to make a hole or mark. This mark in each instance is a reference point for the location, as soon as the stick it takes the place of or represents is removed. The sticks are removed so they will not be in the way of the players during the running of play approach them as the plays continue. Otherwise the players in running out of bounds in their vicinity may run into them and receive severe injuries. However the holes marked in the ground cannot be made conspicuous and are often hard to distinguish afterwards. The result is considerable confusion, disputes, uncertainties in the game, as well as rendering decisions by the umpires questionable in too many instances. The holes are also used as a basis from which to designate the advance made during the four downs or to determine penalty distance. The present method is therefore unsatisfactory because of this uncertainty and the opportunity to make serious mistakes. Also it slows up the game appreciably because the holes marked by the stick are always hard to find by the umpires, because they may be walked on by the players as they walk over them during the play. Since the holes cannot be distinguished beyond a distance of a few feet, they cannot be kept visually under observation when one of the sticks is lifted. In fact their actual locations appear different to the majority of the players and the audience watching the game. In other words this phase of the game offers a source of continual trouble to all concerned.

It is therefore an object of this invention to provide a new and improved method for marking off play-off distances on a football field that will avoid one or more of the disadvantages and limitations of the prior art.

Another object of the present invention is to provide a new and improved method for marking off play-off distances on a football field that will make such distances appreciable and the locations of the markers visually apparent from practically all parts of the field and immediate vicinity.

A further object of the invention is to provide a new and improved method for marking off play-off or penalty distances on a football field in a convenient, quick and safe manner. An additional object of the herein described

invention is to provide a new and improved system of markers for indicating play-off or penal distances on a football field that will be inexpensive to construct, effective in use, easy to handle and manipulate; and positively identifiable.

An additional object of the present invention is to provide an adjunct attachment to be used with the down marker and ten yard marker flags which will be affixed in the ground and left there for future reference when the flags have been removed.

Other objects will become apparent as the invention is more fully set forth.

For clearer understanding of the invention, reference is made to the appended drawings, wherein a particular form of the invention is indicated. These drawings with the following description outline the features and principles of the invention, and indicate the basis for the objects. The particular form is employed simply as an example to illustrate the invention and not by way of limitation to the forms that may be indicated thereby, while the claim particularly points the scope of the invention.

In the drawings:

Figure 1 is a plan view of the playing field showing the down and ten yard markers flags positioned on marker plates embodying this invention;

Figure 2 is a plan view of the ten yard marker plate shown in Figure 1;

Figure 3 is a plan view of the down marker plate shown in Figure 1;

Figure 4 is a sectional view taken along line 4-4 of Figure 2;

Figure 5 is a sectional view taken along line 5-5 of Figure 3, and

Figure 6 is a sectional view of a modified form of marker plate with a rubber covering.

Similar reference characters refer to similar parts throughout the drawings.

In the structures shown in the drawings, a "down" marker plate 10 of metal or other suitable hard material is of circular form, relatively flat except that its peripheral rim portion 17 is bent round and downwardly. The central portion has a circular depression 11 bevelled inwardly at 16 near the upper surface 12 to a conical portion 13 that leads to a pointed or cone-contoured end, that forms the bottom 14 of the depression. This depression is intended to receive the pointed end of an official marker or ten yard stick used in football games, and permits it to be held perpendicular to the ground therein. On the underface of the "down" plate 10 below the material forming the depression structure, a short spike or anchor 15 projects at right angles. This spike or anchor 15 sticks into the ground when the "down" plate 10 is placed on the ground, and serves to anchor it in that location. The upper face 12 of the plate is formed with embossed arms 18 of a four-pointed star raised on it. Each arm 18 is positioned at right angles to those at its sides. The arms are numbered, 1, 2, 3, and 4 in consecutive arrangement thereon, as shown in Figure 3. This plate is termed the "down marker" plate, and is used to show the last down that has taken place.

A second plate 20 called the 10 yard marker plate is similar in size and general form to plate 10, has a depression 21, with bevel 26, conical portion 23 and pointed bottom 24 and spike 22 similar to that of the first or down marker plate. However, the upper surface 82 of this plate 20 is

provided with concentric rings 25 to make it conspicuous and distinguishable from the plate 10. Its rim portion 27 is likewise rounded. It also has a spike or anchor 22 underneath.

Both plates are preferably made of aluminum by reason of its color, lightness and ease of manufacture. However other materials, suitably colored and able to withstand the usage involved could be used, appropriately. The plates are each laid flat on the ground in use, with the anchors 15 and 22 and round rims pressed into the ground. The arrow arms on the top surface of the down marker plate 10 are rotated so that the number, (1, 2, 3 and 4) designating the specific sequence of the "down" in the play off involved is pointed in the transverse direction towards the playing field.

The 10 yard marker plate 20 having round rings impressed on its upper surface to distinguish it, may be set down flat without regard to any direction that it should point to.

In Figure 1, the diagram of a full football field 40 is shown. Its long lateral border lines 41 join the shorter cross border lines 42 at the end zones 43. The five yard cross lines 44 extend transversely across the field as shown and are often designated by their values positioned on the 10 yard lines outside of the field, by suitable numbers 46. The use of these numbers is arbitrary as is also their locations from the borders, but they facilitate an understanding of the relative positions of the teams. They are indicated in circles, on the drawings to distinguish them from the regular reference numerals. The distances start from the goal lines as "G" and reach their maximum values at the center line 47, which is termed the "50-yard line."

The game is started by the selected team kicking the football from the forty yard line. The usual tactics are proceeded with, and eventually the play is stopped, with one of the teams entitled to the football, and a point 49 established from which further play-offs must start. The point 49 from which the football must be started is known as the "first down" line. The official indicates this line by taking a reference point in the side lines and placing a "down" marker plate 10 on it at 51 and the numeral 1 pointed towards the playing field, aligned with the "first down" point. From the "down" plate 10 so located, a ten-yard measuring chain is run towards the goal to which the team owning the football is working or playing. The chain is run in the side line space 55 parallel to the side line set out for the team having the ball, and a point 53 ten-yards away located. A second plate 20 is placed on that point 53. This plate 20 is termed the "ten yard" plate. A line running from this "ten yard" plate transversely across the field indicates the line 52 that the team owning the ball, must advance to before or by the fourth down. This is, of course, assuming that the team retains the ball that long.

The game continues, until the football is brought to another stopping point, 54 with the same team owning it. This point is called the second down. The "down" plate 10 is lifted from its original "first down" location, and placed in the side line space 55 at a point 56 in line with the second down location with the numeral 2 pointing towards the field. In this case, it is assumed to be five yards ahead towards the opponent's goal at 14. If in the next play-off, the football is carried by the same team to a point 57 located fifteen yards in the opposite direction

when it is stopped, the "down" plate 10 is aligned with it at 58 and the numeral 3 pointed towards the field and the play is called the third down. The same team continues with the football from the point 57 for the fourth down and is assumed to have advanced it twenty-five yards to the point 59. The "down" plate 10 is moved to the point 60. This is the result attained by the fourth down, and is more than ten yards advance from the original first down line, which gives the same team the right to repeat the performance, as it still "owns" the ball. The "down" plate 10 remains in line with the point 59 and considered the first down in a new series of plays and the down plate 10 is turned to 1. The "ten yard" plate 20 is likewise relocated ten yards in advance of the point 60 to the location 61 and left there for four more downs, if the same team can make them. Should a foul be incurred by this team, say of ten yards, during any play, then the "down" plate 10 is pushed back ten yards from the point where that particular down started at that play and away from the opponent's goal direction. The "down" marker 10 would move back, but the numeral would not be changed. It is the same as if the team made a loss of ten yards for that play.

In the last "half" the markers are moved to the opposite side of the field having a similar space 55. The plates are located in the side line space at the same place the "down" and "ten yards" flags are located, as a matter of convenience and to get them away from the players' feet. It is also understood to afford a placement less subject to misplacement, intentional or otherwise at these locations. The plates are preferably flat so they will not be obstructive, but may be made of a color to make them conspicuous so they can be seen and identified readily.

The particular forms of the plates shown in the drawings, have the following features. They are both preferably circular and flat with their peripheral rims bent downwardly to dig into the turf or ground of the field or side line space. In the central portion, a circular depression having cylindrically formed walls inside, and pointed to the bottom is adapted to receive and preferably hold onto the end of a conventional marking stick used by officials of the game. This arrangement permits the flags to be lifted up by the stick and carried to various locations during the game and leave the plates in the ground so the flags may be returned to these points as the conditions may require. The entering edge of the depression is bevelled to make it easier for the stick to be centered and inserted therein. A spike termed an anchor projects from the rim to keep each plate in place and from being moved laterally.

The coloring of the plates may also be made to suit any particular conditions that may make them more distinguishable, if desired. The plates may be carried on the end of the marking sticks without any difficulty, as the structure is preferably light, and can be easily placed in position while thereon, with the least physical effort on the part of the officials. When the plates are placed in the ground, the officials may simply press each off with a foot while lifting up the stick in that particular plate.

The plates have the advantage of being easily carried around by officials. They render disputes about locations of the football during the game less liable. They could be used without the sticks. They show up conspicuously on the field, whereas the holes in the ground usually made by sticks

were hardly discernible at any time, and frequently could not be found, rendering the decision of the outcome of the game very much in doubt and subject to question. The audience and players at the game, are assured of accurate marking which previously could not be guaranteed, and the officials of the game were aware of the fact. This removes the burden of identifying locations of "downs" and "ten yard" markers and similar items off the shoulders of the officials because the physical placement of the plates proves them visually and unmistakably during their use. The particular shapes of the plates may be varied to suit particular requirements or to enable them to suit different types of players, or the terrain on which the game is played in many ways, but all are preferably light and flat so they may be easily handled and manipulated and afford any obstruction that might cause them to be easily displaced. In Figure 6 is shown a plate similar to that shown in Figure 4, with a resilient mat 182 added to its face to prevent injury to the player. The mat is provided with concentric rings 125 and a hole in the center. The plate proper is furnished with a circular depression 121 bevelled inwardly at 126 near the upper surface to a conical portion 123 that leads to a pointed or cone-contoured end, that forms the bottom 124 of the depression. The down marker plate 10 may also be furnished with the resilient mat properly marked to show the 4 downs like the illustration shown on the top of Figure 3.

While but two general forms of the invention are shown in the drawings and described in the specification, it is not desired to limit this application for patent to these particular forms or in any other way otherwise than limited by the scope thereof, as it is appreciated that other forms could be made that would use the same principles and come within the scope of the appended claim.

Having thus described the invention what is claimed is:

45 A marker to be used along the longitudinal edges of a football field, consisting of a circular disk having a flat top surface and a short depending centrally arranged stem having a terminal point whereby the marker may be driven in the ground, said stem having an internal hollow depression therein extending from the top surface of the disk and extending downwardly within the stem to a point considerably below the lower surface of the disk, to provide a space for receiving 50 a stick and holding it therein tightly, said disk having a circular depending rim extending downwardly beyond the lower surface of the disk, the upper surface of the disk having distinguishing designs thereon, wherein the distinguishing design consists of embossed arms in quadrant formation, each arm terminating in a point at the periphery of the disk and bearing indicia whereby the particular arm pointed towards the field gives a visual indication of the down to be played.
